UNITED STATES PATENT OFFICE.

JOSEPH H. POWERS, OF ELKHORN, WISCONSIN.

STORM-APRON DEVICE.

No. 905,455.

Specification of Letters Patent.

Patented Dec. 1, 1908.

Application filed February 11, 1908. Serial No. 415,404.

To all whom it may concern:

Be it known that I, JOSEPH H. POWERS, a citizen of the United States, residing at Elkhorn, in the county of Walworth and State 5 of Wisconsin, have invented certain new and useful Improvements in Storm-Apron Devices, of which the following is a specification.

My invention relates to improvements in storm apron devices for vehicles, its object 10 being, among other things, to provide a spring controlled apron which can be readily manipulated and automatically rolled up when not in use.

More particularly the invention consists 15 in the construction, combination and arrangement of parts hereinafter described and claimed.

In the accompanying drawings forming 20 part of this specification, Figure 1 is a perspective view of the body of a buggy fitted with my improvements, the apron being shown drawn out and secured in protecting position; Fig. 2 is a vertical longitudinal 25 section through the casing and rollers on line $w-w$ of Fig. 4; Fig. 3 is a horizontal section on line $v-v$ of Fig. 2; Fig. 4 is a vertical cross section through the casing and rollers on line $y-y$ of Fig. 2; Fig. 5 is a vertical cross 30 section through the roller casing on line $z-z$ of Fig. 2, showing the rollers in elevation; Fig. 6 is a detail of the locking mechanism shown in Fig. 3, but with the parts in locking 35 position; Fig. 7 is a perspective detail of the actuating rod for the locking mechanism, the locking lever being shown partly broken away; Fig. 8 is an elevation of the grooved wheel forming part of the locking 40 mechanism; Fig. 9 is a section thereof on line $x-x$ of Fig. 8, showing a fragment of the locking pin; Fig. 10 is a perspective 45 view of the rock frame which intercepts and holds the apron roller against the tension of its spring; Fig. 11 is a horizontal section through the apron when the side flaps are 50 folded over in position to be rolled up; Fig. 12 is an elevation of a fragment of the apron casing, viewed from within the vehicle, showing the slots for holding the side flaps 55 of the apron; Fig. 13 is a view of one of the slots upon an enlarged scale, showing a flap held therein under spring pressure; Fig. 14 is a top view of the roller casing; Fig. 15 is a longitudinal section through one of the 55 slots showing in dotted lines a flap portion

therein inserted, and Fig. 16 is a side elevation of a fragment of a buggy body showing the apron drawn out to cover the knees of the driver.

In the drawings A represents the body of the vehicle, B the canopy and C the dashboard. Integral with the dashboard, or secured to it in any suitable way, is a casing D having end walls 3 within which is arranged a spring roller 2 which carries a storm 60 apron E.

As shown in Figs. 2 and 3 the roller 2 is a hollow cylinder journaled upon the axle or spindle 4 which has its ends secured in the end walls or supports 3. Arranged within the roller are one or more helical springs 5 surrounding the axle and having one end secured to the roller and the other end to the axle. The apron is secured at one end 70 to the roller and passes thence over the idler roller 6, and then up over the rollers 7 and 8 as shown in Fig. 4, these rollers being journaled in the supports or end walls 3 of the casing.

Revolutely mounted upon the shaft 9 of 80 the roller 7 is a rocking shell 10 arranged above said roller and below the horizontal bar 11 which extends across the casing between the rollers 7 and 8, as best shown in Figs. 2 and 5. The shell is formed with projecting curved lips 12 arranged in position to intercept and hold the ends of the stick 13 which is secured along the top of the front portion of the apron. The shell is held normally in upturned position with the lips 12 85 thrown against the bar 11, as shown in Fig. 4, by means of coil springs 14 secured at one end to the shell and at the other end to the casing D; the bar thus serving as a stop to intercept the lips and prevent the shell from 90 turning farther.

Revolutely mounted on the shaft 15 of the upper roller 8 is another shell 16, provided at each end with a projecting bearing lug 17 which fits loosely over the shaft 15 of 100 the roller 8. The lugs are shown rectangular in section, and against each lug rests a spring strip 18 secured to the bar 11. This strip bearing against one of the flat sides of the lug will normally hold the shell from 105 turning.

When the apron is rolled down out of the way the parts will stand in position shown in Fig. 5 with the rod 13 intercepted and held by the lips 12 against the tension of the 110

spring 5, the lips themselves being held by the springs 14. When it is desired to pull up the apron, the rod 13 is grasped and the apron pulled out against the tension of its spring 5, as illustrated in Fig. 4. If it is desired to secure the apron upon the canopy of the vehicle the apron will pass directly up alongside the rollers 7 and 8, as shown in Fig. 4, freeing the shell 10, which will be turned up by its spring against the bar 11. The flaps 19, which, when the apron was rolled up, were folded over upon the apron as shown in Fig. 11, are pulled out and buttoned or otherwise secured to the carriage body and the canopy, as shown in Fig. 1, the shell 16 being turned by hand over the roller 8 so as to shield it. It will be observed that the ends of the rod 13 project out through the apron at the corners of the canopy in position to be intercepted by the lips 12. When it is desired to have the apron rolled up again, it is only necessary to fold the flaps 19 over against the inner side of the apron, to release the apron from the canopy and to turn the shell 10 down so that its lips 12 will intercept the ends of the rod 13.

When it is desired to use the apron as a lap robe, the shell 16 is turned over upon its side, as shown in Fig. 5, so as to permit the apron to pass over the top of the roller without obstruction. The use of the apron in this way is illustrated in Fig. 16.

In use it will be found convenient to draw the apron out a certain distance and then secure it against being accidentally pulled or blown farther out, for, in driving against the wind, the wind will exert a tendency to unroll the apron, disarranging its position and subjecting the spring and roller to unnecessary working. To prevent this the locking mechanism about to be described is provided.

Passing loosely through one end 20 of the roller 2 is a spring pressed locking pin 21, held normally thrust out of the end of the roller by means of the pressure of the spring 22. As shown in the drawings the end 20 of the cylinder is cored out to permit the spring to be inserted within the same, and the pin 21 is provided with an inturned inner end 23 which forms a stop to prevent the pin from being thrust too far out of the cylinder end. Rotatably mounted upon the shaft 4 of the roller 2 adjacent to the end of the pin 21 is a disk 24 which is capable of being moved longitudinally upon the shaft. This disk is formed with a groove 25 which starts at 26 flush with the inner face of the disk and extends around concentrically with the axle 4, growing progressively deeper towards its other end 27, which is close to the starting point. The groove and pin are so arranged that the pin will enter the groove 65 when the disk is thrust inward towards the

roller. The disk is operated back and forth by means of a lever 28 having one end extending into a socket 29 in the periphery of the disk. The other end of the lever is connected with a rod 30 which extends within the casing and passes out through a slotted hole 31 therein, terminating in an operating handle 32. To lock the roller against unrolling the apron, it is only necessary to push the handle 32 sidewise. This will cause the lever 28 to throw the disk 24 in towards the roller so that the pin 21 will enter the groove 25. Now, when the apron is drawn out farther, the pin 21 will travel around in the groove 24 until it abuts 80 against the end wall at the deepest end 27 of the groove. This will prevent further turning in that direction, but will not prevent the roller from turning in the opposite direction.

As a convenient means for holding the 85 flaps of the apron when not in use I form the inner face of the casing with two narrow slots or sockets 33 each of sufficient width to receive one of the flaps 19, as shown in Figs. 13 and 15. To hold the flaps securely 90 therein I arrange in each socket a spring strip 34 to pinch the flap. In the drawings the rod 30 is shown bent at 35 to clear the socket.

It is obvious that the details of the device 95 may be variously modified without departing from the principle of the invention, the scope of which is defined in the claims.

I claim as my invention:

1. The combination, with the dashboard 100 of a vehicle, of end-supports carried thereby, a spring roller mounted in said supports, idler rollers also mounted therein, a storm apron secured to the spring roller and passing up over the idler rollers, a rod secured 105 along the free end of the apron, and a lip rotatably mounted within the end-supports in position to intercept and hold said rod.

2. The combination, with the dashboard 110 of a vehicle, of end-supports carried thereby, a shaft mounted in said supports, a spring roller revolvably mounted upon said shaft, a storm apron secured to the roller, a grooved disk revolvably and slidably mounted upon the shaft, the groove being concentric with 115 the shaft and growing progressively deeper, a spring pressed pin longitudinally slidable in the adjacent end of the roller and having a projecting end adapted to fit into said groove, and mechanism for sliding the disk 120 into co-operative relation with the pin.

3. The combination, with the dashboard 125 of a vehicle, of a casing carried thereby, a spring roller mounted in the ends of the casing, idler rollers also journaled in the ends 130 of the casing above the spring roller, a storm apron secured to the spring roller and passing up over the idler rollers, a rod secured along the free end of the apron, and spring controlled means rotatably mounted within

the casing in position to intercept and hold said rod against the tension of the roller spring.

4. The combination, with the dashboard 5 of a vehicle, of a casing carried thereby, a spring roller rotatably mounted in the casing, a storm apron comprising a front portion and side flaps secured to the spring roller along the bottom of the front portion, 10 the casing being formed with vertical slotted

sockets in position to receive the end edges of the flaps, and a spring arranged within each socket for holding said flaps elastically therein.

In testimony whereof I affix my signature 15 in presence of two witnesses.

JOSEPH H. POWERS.
